(57) **CLAIM**

The ornamental design for a match striker, as shown and described.

DESCRIPTION

FIG. 1 is a perspective view of my new design for a match striker.

FIG. 2 is a side view of the design shown in FIG. 1.

FIG. 3 is a top view of the design shown in FIG. 1; and, FIG. 4 is a bottom view of the design shown in FIG. 1. In the drawings, the matches shown in broken lines in FIGS. 1-4 are environmental subject matter only and form no part of the claimed design; all the other broken lines in the drawings depict portions of the match striker that form no part of the claimed design.
